CLAIM

The ornamental design for a storage case for binoculars, as shown and described.

DESCRIPTION

FIG. 1 is a front perspective view of a storage case for binoculars showing my new design, the inner portion which is not shown being substantially identical to the visible side except for the inner scored lines;

FIG. 2 is a top plan view thereof;

FIG. 3 is a bottom plan view thereof;

FIG. 4 is a front-elevational view thereof;

FIG. 5 is a right side elevational view thereof;

FIG. 6 is a left side elevational view thereof; and,

FIG. 7 is a rear-elevational view thereof.

FIG. 1

FIG. 2

FIG. 3

FIG. 4

FIG. 5
